US0D1112583S

(12) **United States Design Patent** (10) Patent No.: **US D1,112,583 S**
(45) Date of Patent: ** Feb. 10, 2026

(54) **ANIMAL REPELLENT DEVICE**

(71) Applicant: **Na Yao**, Anhui (CN)

(72) Inventor: **Na Yao**, Anhui (CN)

(**) Term: **15 Years**

(21) Appl. No.: **29/979,542**

(22) Filed: **Dec. 19, 2024**

(51) LOC (15) Cl. **22-06**

(52) U.S. Cl.

USPC **D22/120**

(58) **Field of Classification Search**

USPC D22/119, 120, 122; D26/67; D13/102
CPC A01K 15/023; H02S 40/34; H01L 31/042

See application file for complete search history.

(57) **CLAIM**

The ornamental design for an animal repellent device as shown and described.

DESCRIPTION

FIG. 1 is a perspective view of an animal repellent device showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash-dash broken lines in the drawings depict portions of the animal repellent device that form no part of the claimed design.

1 Claim, 8 Drawing Sheets
